CLAIM

The ornamental design for a telephone set, as shown and described.

DESCRIPTION

FIG. 1 is a front, top and right side perspective view of a telephone showing our new design;

FIG. 2 is a front elevational view thereof with the cord shown in abbreviated form in this and in FIGS. 3-7 for convenience of illustration;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and

FIG. 8 is a front, top and right side perspective view thereof with the handset removed from the base and inverted.
